[57] **CLAIM**

The ornamental design for a retaining device for maintaining corrected dentition, as shown and described.

DESCRIPTION

FIG. 1 is a perspective view, taken from the front, top, right corner of a retaining device for maintaining corrected dentition showing my new design;

FIG. 2 is a top view thereof;

FIG. 3 is a bottom view thereof;

FIG. 4 is a right side view thereof, the left side view being a mirror image thereof;

FIG. 5 is a front view thereof; and,

FIG. 6 is a rear view thereof.
